A new and useful method of making a soap and a new metal soap, and more particularly, a method of making a soap and metal soap which may be prepared by treating talloil with a suitable metal sulfate, the resulting metal soap being obtained in a relatively stable form.

UNITED STATES PATENT OFFICE

2,381,822

METHOD OF MAKING METAL SOAPS

Paul Hodges, Crossett,
States Paper Corporation,
Delaware

No Drawing. Application February 8, 1943.
Serial No. 475,224

5 Claims. (Cl. 260—97.5)

My invention relates to soaps of the heavy metals and alkaline earth metals derived from what is known in the paper industry as "floating soap" which is collected from the black liquors of the sulfate and soda processes for obtaining cellulose fibres. This "floating soap" has been variously designated in the literature as "sulfate soap," "sodium oleo-resinate," "black liquor soap," "sulfate skimmings," and "resolein."

"Floating soap" is essentially the sodium salt of the oleo-resinous part of the tree. It is formed during the cooking reaction and on standing floats to the top of the spent solution. The analysis, the physical properties and chemical properties of "floating soap" vary to a certain extent, depending on the conditions of its manufacture, and the woody material from which it is obtained. Analyses published indicate the presence of the sodium salts of abietic, pimamic, levopimamic, pyro abietic, oleic acid, and linolenic acid, free sodium hydroxide, free sodium sulfide, sodium lignate, free sodium carbonate, and sterols. A broad designation of the material as sodium oleo-resinate is possibly as accurate, chemically, as can at the present be devised. If we broadly classify the acids as abietic and fatty acids, then the analysis will vary approximately between:

	Percent
Moisture	35—40
Soda (as Na)	3.5—4.5
Sterols	3.8—4.5
Abietic acids	25—30
Fatty acids	25—30

Depending on the type of wood used the fatty acid fraction is some times as much as 5% greater than the abietic content, and with other types the abietic fraction is the greater.

I have found that metallic oleo-resinates of the heavy metals such as copper, aluminum, calcium, lead, manganese, magnesium, mercury, nickel, zinc, tin, silver and others hereinafter mentioned, may be readily prepared from "floating soap."

It has heretofore been proposed to make heavy metal and alkaline earth soap from talloil which, broadly, is a mixture of fatty and resinic acids derived from "floating soap." Talloil may, among other methods, be obtained by treating "floating soap" with an acid which will liberate the fatty and resinic acids in the soap, and then subjecting the product to suitable purifying processes. For example see Michelson Patent No. 1,823,752, dated September 15, 1931. It is a principal object of this invention to provide a process

for producing metallic oleo-resinates which are relatively stable, and which may be prepared directly from "floating soap" without the use of acids, and which may be used as driers in paints, varnishes, inks and like products, and differ in physical and chemical properties from mixtures of commercial oleates, lino-

5 for producing such soaps directly from the crude "floating soap," and without the necessity of first separating talloil therefrom.

By way of example, the preparation of metallic oleo-resinates directly from "floating soap" may be carried out as follows:

A hot concentrated water solution of a soluble salt of the metal of which the oleo-resinate is desired; for instance copper sulfate, is added slowly, while stirring, to the "floating soap." As the solution is added, a precipitate of the corresponding metallic oleo-resinate occurs and when the soluble salt of the metal is in excess the metallic oleo-resinate is completely separated out. In the case of copper this is a dark green plastic mass. The oleo-resinates separate to the top and may be removed from the reaction mixture. Dilute solutions of both the salt and the "floating soap" can be used either hot or cold to prepare the oleo-resinate desired, but the reaction will not proceed at the same rate as if carried out in the manner just described.

The final product may be washed and dried and is then ready for use. In the case of some of the more soluble oleo-resinates, it is advantageous to use sodium chloride solutions to wash the soap.

The reaction producing these soaps is one of double decomposition in which the sodium oleo-resinate or "floating soap" reacts with a soluble salt of the metal. For example, when the sodium oleo-resinate or "floating soap" reacts with copper sulfate, the oleo-resin and SO₄ radicals exchange places, producing copper oleo-resinate and sodium sulfate. If desired, the sodium sulfate in such a reaction may be recovered. In like manner, the nitrates, chlorides, acetates, or any other water soluble salt of the metal whose oleo-resinate is sought may be used and the corresponding sodium salt formed.

Inasmuch as the sulfates of calcium, lead, silver, and some other metals are relatively insoluble, the use of sulfates of such metal would be either impossible or inadvisable, while the nitrates of such metals may be used. In the case of lead, mercurous mercury and silver, the chloride may not give a complete reaction. In any case, the salt employed will be that soluble salt of the metal in which the metallic radical content is least expensive.

The oleo-resinates produced as hereinbefore described from "floating soap" are useful as driers in paints, varnishes, inks and like products, and differ in physical and chemical properties from mixtures of commercial oleates, lino-

leates and resinates heretofore used as driers. Also products made in accordance with my invention are particularly useful as constituents in varnishes, paints and the like, in which they may be employed to take the place of resins, shellac, waxes, and like substances heretofore employed.

Among other uses I have found that the products made according to my invention are useful for coating and glazes and metal lusters on ceramics; as insecticides, germicides and fungicides when prepared from salts of the poisonous metals; as water repellant agents for paper, textiles, concrete, and similar uses, and other important uses in which they replace more expensive products heretofore known in the art.

Useful soaps may be made, in accordance with my invention, from water soluble salts of aluminum, lead, calcium, magnesium, manganese, iron, cobalt, nickel, mercury, arsenic, barium, bismuth, chromium, copper, antimony, tin, zinc, and other less common metal elements.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. The process of producing a metal soap of

the heavy metals and alkaline earth metals which comprises reacting a water solution of a compound of the metal selected from the group consisting of heavy metals and alkaline earth metals with "floating soap" collected from black liquor in the manufacture of cellulosic material by the sulfate or soda process.

2. The process of producing a metal soap of the heavy metals and alkaline earth metals which 10 comprises reacting a hot concentrated water solution of a compound of such a metal with "floating soap" collected from black liquor in the manufacture of cellulosic material by the sulfate or soda process.

15 3. The process of producing a copper soap which comprises reacting copper sulfate with "floating soap" collected from black liquor in the manufacturer of cellulosic material by the sulfate or soda process.

4. The process of producing an aluminum soap which comprises reacting a water soluble aluminum compound with "floating soap" collected from black liquor in the manufacture of cellulosic material by the sulfate or soda process.

25 5. The process of producing cobalt soap which comprises reacting a water soluble cobalt compound with "floating soap" collected from black liquor in the manufacture of cellulosic material by the sulfate or soda process.

PAUL HODGES.
